UNITED STATES PATENT OFFICE.

EDWARD C. WALKER, OF ST. LOUIS, MISSOURI, ASSIGNEE TO NATIONAL LEAD COMPANY, OF NEW YORK, N. Y., A CORPORATION OF NEW JERSEY.

BARREL.

Application filed May 18, 1923. Serial No. 639,747.

This invention relates to barrels and similar containers.

One of the objects of the invention is to provide a container, such as a barrel, which shall be strong and rugged so as to withstand rough usage, and which shall be cheap and simple to construct.

Another object of this invention is to provide such a container with a closing cover or barrel head which is itself rigid and which may be securely fixed in place.

Another object of this invention is to provide a container with a cover which shall have a secure seat in the container so that a tight seal may be obtained when the cover or head is locked in place.

Another object of the invention is to provide a novel method of securing the head to the barrel in such a way as to provide a tight seal and at the same time to be easily removable.

Further objects will appear from the detail description taken in connection with the accompanying drawing, in which:

25 Figure 1 represents a side elevation, partly in section, of a barrel embodying this invention;

Figure 2 is an enlarged sectional detail showing the structure of the rim of the barrel head and the locking ring before said ring has been turned under to seal the barrel;

Figure 3 is a view similar to Figure 2 showing the locking ring turned under; and

35 Figure 4 is a similar view showing the barrel head secured by clips instead of a locking ring.

Referring to the accompanying drawing, 1 designates the body of the barrel which in 40 the present instance is constructed of sheet metal of fairly heavy gauge and having the ordinary bellied outline to insure rigidity. The base 2 may be of any suitable well known construction.

45 In order to form the upper rim of the barrel, the body portion 3 is flared outwardly for a certain distance to form a tapered portion 4 adapted to provide a seat for the correspondingly tapered rim 5 of the barrel head. Outside of the tapered portion 4 the rim is reenforced by a strip 6, practically coextensive with the seat 4 and the upper portion of the rim is further reenforced by a narrower strip 7. The material of the barrel itself is formed over these strips by bend-

ing downwardly outside of the strip 7 and then crimping the same under this strip as shown at 8. The material thus rolled over these strips and crimped under the strip 7 forms a bead of considerable thickness which 60 not only strengthens the rim of the barrel but also provides means for securing the head in place as will presently be described.

The head of the barrel is formed with a dished body portion 9 and has its edges 65 turned up to form a tapering rim 5 adapted to fit the tapered seat 4 described above. The upper edge of the rim 5 is turned outwardly to form a flange 10 adapted to rest on the rim of the barrel when the head is in 70 place. The flange 5 may be formed to provide a snug fit in the seat 4 so that when the head is forced into said seat, a very tight seal is provided. In order to secure the head in place on the barrel a ring 11 is provided 75 which is formed with a top flange 12 adapted to rest upon the flange 10 of the barrel head when the latter is in place. This flange 12 may be formed so as to fit snugly over the flange 10. The ring is also provided with a 80 vertical flange 13 adapted to slip over the bead on the rim of the barrel as illustrated in Figure 2. When the ring 11 is first applied the flange 13 is straight as shown in Figure 2. When the barrel head has been 85 forced down until the flange 10 rests on the rim of the barrel and the ring 11 has been slipped over the same and forced down until it rests firmly on the flange 10, the flange 13 may be turned under the bead as shown at 90 14, Figure 3, by means of a suitable tool or machine. The ring being constructed of heavy sheet metal similar to that of the barrel itself, the head will thus be securely held in place and the barrel effectively sealed.

95 Containers of this kind are often used for shipping materials, such as white lead, which are in fluid or semi-fluid form and which have considerable weight and a stout container and a method of securely sealing 100 the same is necessary. This invention, therefore, provides a substantial and rugged container and simple but effective means for securely sealing the same. When the loaded barrel arrives at its destination it may be 105 opened by tearing the ring 11 off by means of a suitable tool after which the head may be worked off by inserting a suitable wedge-shaped tool between the flange 10 and the rim of the barrel. The ring 11, of course, 110

is destroyed in opening the barrel. As these barrels are usually used over and over again, arrangements are made for their return to the sender when the contents have been removed. In that case the barrel head must, of course, be returned with the barrel. Since the ring 11 has been destroyed, however, other means must be provided for holding the head in place during the return journey and for this purpose suitable clips 15, formed as illustrated in Figure 4 and constructed of suitable spring metal, are provided. These clips are snapped over the barrel head and take under the bead in a manner similar to the action of the ring 11 and as illustrated in Figure 4. A number of these clips are spaced around the rim of the barrel and effectively maintain the head in place.

20 It will be seen, therefore, that the invention accomplishes its objects. A container is provided which is strong and rugged and which may be effectively sealed and the seal secured. The construction is simple and inexpensive and mechanically strong throughout.

It is obvious that various changes may be made in details without departing from the

spirit of this invention; it is, therefore, to be understood that this invention is not to be limited to the specific details shown and described.

Having thus described the invention, what is claimed is:

1. A barrel, the end of which is formed to provide a concave seat and curled outwardly over a reinforcing ring to provide a bead, a head having a flange adapted to engage said seat, and a continuous ring adapted to be slipped over the barrel end so as to bear on said head, said ring having a depending flange adapted to be turned against the barrel end so as to crown said bead into the seat portion.

2. A barrel, the end of which has a tapering inside seat, terminating in an external bead, a head having a corresponding tapering flange adapted to engage said seat, and a continuous ring adapted to be slipped over the barrel end so as to bear on said head, said ring having a depending flange adapted to be turned against the barrel end whereby said bead is forced into the seat portion.

In testimony whereof I affix my signature this 21st day of March, 1923.

EDWARD C. WALKER.
